United States Patent Office

Des. 187,833
Patented May 3, 1960

187,833

REVERSING VALVE

Herman L. Dilliner, Chicago, Ill., assignor to Indico Valve Corporation, Chicago, Ill., a corporation of Illinois

Application June 27, 1958, Serial No. 51,572

Term of patent 14 years

(Cl. D78—1)

Fig. 1 is a front perspective view of a reversing valve, showing my new design;

Fig. 2 is a rear perspective view thereof; and

Fig. 3 is a bottom plan view thereof.

I claim:

The ornamental design for a reversing valve, as shown.
